(57) CLAIM

The ornamental design for a connector with instruments, as shown and described.

DESCRIPTION

FIG. 1 is an isometric view showing one side of a first embodiment of my new design where the instrument on one side is a compass and the instrument on the other side may either be a thermometer or a clock;

FIG. 2 is an isometric view showing one side of a second embodiment of my new design where the instrument on one side is a thermometer and the instrument on the other side may either be a compass or a clock;

FIG. 3 is an isometric view showing one side of a third embodiment of my new design where the instrument on one side is a clock and the instrument on the other side may either be a compass or a thermometer;

FIG. 4 is a side elevational view of the first, second and third embodiments;

FIG. 5 is a front elevational view of the first, second and third embodiments;

FIG. 6 is a rear elevational view of the first, second and third embodiments;

FIG. 7 is a top plan view of the first embodiment, having a complimentary connector inserted therein shown in phantom, which does not form a part of the invention;

FIG. 8 is a top plan view of the second embodiment; and,

FIG. 9 is a top plan view of the third embodiment.
